UNITED STATES PATENT OFFICE.

VINTON E. SISSON, OF CHICAGO, ILLINOIS, ASSIGNOR TO WALTER P. MURPHY, OF CHICAGO, ILLINOIS.

PRESSED-STEEL CAR END.

1,265,714.

Specification of Letters Patent.

Patented May 7, 1918.

Application filed June 23, 1913. Serial No. 775,294.

To all whom it may concern:

Be it known that I, VINTON E. SISSON, a citizen of the United States, residing at Chicago, in the county of Cook and State of Illinois, have invented certain new and useful Improvements in Pressed-Steel Car Ends, of which the following is a specification.

My invention relates to the construction of railway cars, particularly box cars, and has for its object to provide a sheet metal end structure for railway cars which may be securely attached to the car, for example, to the framing of a wooden box car of standard type, either new or old, and is so constructed that it will effectively withstand the cargo thrusts, pressures and impacts to which the end of a railway freight car is subjected, and so that, furthermore, it will strengthen the whole car structure against the racking strains incident to the use of a car under ordinary service conditions.

A specific object of the invention is to provide a sheet steel car end comprising a plurality of end sheets which are formed, for strength and rigidity, with pressed out ribs or corrugations and with overlapping margins conformed and arranged so as to provide, in effect, a reinforcing band or girth having greater strength and rigidity than the rest of the end, the invention contemplating preferably a disposition of the pressed out ribs of the sheets at right angles to this band or girth so that the structure is capable of withstanding stresses and pressures from all directions without undesirable deflection.

The invention has for further objects such other new and improved constructions, arrangements and devices relating to sheet metal car ends as will be hereinafter described and claimed.

The invention is illustrated in a preferred embodiment in the accompanying drawings, wherein—

Figure 1 is an end elevation of the body of a wooden box car of familiar type equipped with a sheet metal end constructed in accordance with my invention;

Fig. 2 is a vertical sectional view taken on line 2—2 of Fig. 1;

Fig. 3 is a fragmentary vertical section

on line 3—3 of Fig. 1, or line 3—3 of Fig. 4; and

Fig. 4 is a sectional plan taken on line 4—4 of Fig. 3.

Like characters of reference designate like parts throughout the several figures of the drawings.

Referring to the drawing, 25 designates an end sill of a wooden box car of ordinary construction, 26 the corresponding end plate, 27 the corner post and 28 the flooring of a car.

The end structure consists, in this illustrative form of the invention, of two end sheets 29 and 30 which are provided on their vertical edges with flanges 31 overlapping the corner posts and secured thereto by suitable means. The sheets are formed with vertically disposed or substantially vertically disposed ribs or corrugations 32 which terminate within the edges of the respective plates and are preferably spaced apart distances equal to their width giving the sheet, in each case, uniformity of reinforcement by dividing it into a series of ribs of substantially equal strength. The upper sheet has a flat flange 33 which may be secured to the end plate 26 by bolts 34, and the lower sheet a similar flange 35 which preferably extends down over and covers the outer face of the end sill 25, being secured thereto by lag screws 36 or other suitable attaching devices. Riveted to the inside of the lower sheet 30 is an angular member 37, the horizontal flange of which is secured to the end sill by bolts 38 and preferably intervenes between the end sill and the flooring of the car. The function of this angular member is four-fold. It provides effective means for securing the lower end sheet to the framing of the car. By intervening between the sill and the flooring it makes the car grain-proof at this place. It reinforces and strengthens the lower portion of the end structure against the inertia thrusts of the cargo at the place where reinforcement is particularly required. Heavy articles such as rails and pipe are usually placed down low in the car and it is such articles as these that are most likely to injure and break out the end of the car by their shifting movements when the train is started or stopped.

Fig. 1 is an end elevation of the body of a wooden box car of familiar type equipped with a sheet metal end constructed in accordance with my invention;

Fig. 2 is a vertical sectional view taken on line 2—2 of Fig. 1;

Fig. 3 is a fragmentary vertical section

The use of a separate angle member for securing the lower end sheet to the framing of the car permits the end sheet to be carried down over the wooden end sill so as to sheath 5 the same.

The lower marginal flange 39 of the upper end sheet 29 overlaps the upper marginal flange 40 of the lower sheet 30. A channel-shaped girth member 41 is secured to the 10 lower sheet by a line of rivets 42 arranged between the inwardly pressed ribs 32 of the latter sheet and to both the upper and lower sheets by a line of rivets 43 passing through the marginal portions 39, 40 of 15 said sheets. The girth member is preferably provided with angular flanges 44 which may be secured by any suitable means to the corner posts 27, for example, by the bolts 45. By this arrangement a central zone or band 20 is provided extending across the car from side to side, which derives its strength and rigidity from the overlapping of the sheets, from the channel formed girth member and, furthermore, from the fact that the ends of 25 the ribs on the lower sheet extend up into this portion of the structure. Gusset plates 46 may be employed for aiding in anchoring the end sheets to the car framing.

Because of the arrangements described 30 the car end is not only capable of withstanding the heaviest sort of cargo thrusts without appreciable deflection, but also serves to carry some of the roof load and, moreover, provides an efficient means for resisting the 35 weaving and other similar stresses to which the railway box car is subjected when in service. The end, therefore, serves to strengthen and rigidify the entire structure of the car instead of being the weakest part 40 of the car structure, as is usually the case in ordinary box car constructions.

I claim:

1. The combination with the end framing of a railway car, of a sheet metal end for 45 the car comprising an end sheet formed with pressed vertical stiffening and reinforcing ribs, an angular member secured to the lower portion of said end sheet and anchored to the

under frame of the car, and a channeled, transversely extending reinforcing member 50 provided with marginal flanges secured to the upper edge of the sheet.

2. The combination with the end framing of a railway car, of a sheet metal end for the car comprising an end sheet formed with 55 pressed vertical stiffening and reinforcing ribs, an angular member secured to the lower portion of said end sheet and anchored to the under frame of the car, and a channeled, transversely extending reinforcing member 60 provided with marginal flanges secured to the upper edge of the sheet, and with end flanges which overlap and are secured to the side members of the end framing of the car.

3. The combination with the body of a 65 railway car, of a metal end structure for the car comprising an end sheet, an angular, transversely extending member at the bottom of the car body to which the lower edge 70 of the end sheet is secured, and means providing a channeled, transversely extending member at the upper edge of the sheet, said sheet being formed with corrugations which extend from substantially the lower to the 75 upper edge of the sheet so as to distribute stresses on the end sheet to the aforesaid transversely extending members.

4. The combination with the body of a railway car, of a metal end structure for the car comprising an end sheet formed with 80 substantially vertical corrugations which terminate within the edges of the sheet and are spaced distances apart substantially equal to their width whereby the corrugated portion of the sheet consists in effect of a series of 85 ribs which function as beams of substantially equal strength, and means constituting transverse stiffening members at the upper and lower edges of the sheet which transmit the stresses from the corrugations to the body of 90 the car.

VINTON E. SISSON.
